UNITED STATES PATENT OFFICE.

ARTHUR M. CORNELL, OF CHICAGO, ILLINOIS, ASSIGNOR TO PETTIBONE-MULLIKEN COMPANY, A CORPORATION OF NEW YORK.

SWITCH-STAND-LEVER LOCK.

Application filed March 14, 1924. Serial No. 699,378.

To all whom it may concern:

Be it known that I, ARTHUR M. CORNELL, a citizen of the United States, residing at Chicago, in the county of Cook and State 5 of Illinois, have invented a new and useful Improvement in Switch-Stand-Lever Locks, of which the following is a specification.

My invention relates to an improvement 10 in the class of devices provided on railway switch-stands for locking the operating lever in its pendent position, wherein it hangs through a notch in the stand-table for retaining the switch in its thrown position.

15 The primary object of my improvement is to provide means of simple but highly effective construction for automatically and releasably locking the lever, when turned on its fulcrum at the end of a throw to 20 hang through a table-notch, and thus prevent it from being accidentally displaced from its switch-retaining position, as by jarring of a train passing through the switch, and thus producing faulty setting thereof.

25 In the accompanying drawings—

Figure 1 is a broken view showing, in perspective, the upper portion of a switch-stand provided with my improvement;

Figure 2 is a section on line 2—2, Fig. 1;

30 Figure 3 is a section on line 3—3, Fig. 2, showing the gravity-latch in its lever-locking engagement;

Figure 4 is a similar view showing the gravity-latch turned to release the lever;

35 Figure 5 is a section on line 5—5, Fig. 2, and

Figure 6 is a partly broken and perspective view of the lever and gravity-latch in disassembled relation.

40 The switch-stand A represented in the drawings is of known construction, and only enough thereof is illustrated to enable my improvement and its co-operation with the stand to be readily understood from the 45 following description.

The table 7, provided with the usual lever-receiving notches 8 and through which the rotatable target-shaft 9, or spindle passes, is surmounted by the head 10 secured to 50 the rotatable shaft and between the jaws 11 of which the throw-lever 12 is fulcrumed at 12^b.

For my purpose I form an extension 10^a on the head 10 to project laterally therefrom at right angles to the direction of

throw of the lever 12, which is provided in its shorter end with a notch 12^a. In the housing is journaled through its head a latch 13, shown at 14 to be weighted to cause it to tend to assume by gravity the lever-locking position represented in Fig. 3, wherein the nose-portion 13^a of the head enters the notch 12^a in the lever-end when the lever is in thrown position and depending through a table-notch 8. The latch thus 60 obstructs raising of the lever on its fulcrum and locks it against accidental displacement.

For enabling the lever 12 to be raised for throwing, the operator tilts the latch by its depending handle-portion to the position 70 represented in Fig. 4, whereby the latch-head is withdrawn from the lever-notch 12^a, thus releasing the lever; and since in turning the lever the notch therein is brought 75 out of registration with the latch-head, the latter is obstructed against re-entering the lever-notch until the throw of the lever is completed and it is introduced into the proper table-notch in its depending position, wherein the notch 12^a again registers 80 with the latch-head and permits the latch to resume the position represented in Fig. 3 with its nose in locking engagement with the lever.

The hole shown at 15 in the handle of the 85 gravity-latch is provided to receive the hasp of a padlock (not shown), if desired for locking the latch against unauthorized disengagement thereof with the operating lever.

I realize that considerable variation is 90 possible in the details of construction herein shown and described, and I do not intend to be limited thereto except as pointed out in the appended claims, in which it is my intention to claim all the novelty inherent in my invention as broadly as permissible by the state of the art.

I claim:

1. In combination with a switch-stand 100 having a lever-retaining table and a head secured to the rotatable target-shaft, a throw-lever fulcrumed on said head and provided with a notch, and a gravity-latch journaled to work at right-angles to the lever-fulcrum and comprising a handle terminating in a head in position to automatically and releasably engage said lever-notch when registering with said latch. 105

2. In combination with a switch-stand 110

having a lever-retaining table and a head secured to the rotatable target-shaft, a throw-lever fulcrumed on said head and having a notch in its shorter end, and a gravity-latch on a journal extending at right-angles to the lever-fulcrum, said latch comprising a handle terminating in a head in position to automatically and releasably engage said lever-notch when registering 10 with said latch-head.

3. In combination with a switch-stand

having a lever-retaining table and a head secured to the rotatable target-shaft, a throw-lever fulcrumed on said head and having a notch in its shorter end, a housing 15 projecting from said head, and a latch having a head and a weighted handle-portion and journaled in said housing to gravitally and releasably engage the latch-head with said lever-notch when registering therewith.

ARTHUR M. CORNELL.
